UNITED STATES PATENT OFFICE.

HARRY F. SCHWARTZENBERG, OF CHICAGO, ILLINOIS, ASSIGNOR TO WILLIAM H. MINER, OF CHICAGO, ILLINOIS.

DRAFT-YOKE FOR RAILWAY-CAR DRAFT-RIGGING.

1,172,742.

Specification of Letters Patent. Patented Feb. 22, 1916.

Application filed March 9, 1914. Serial No. 823,284.

To all whom it may concern:

Be it known that I, HARRY F. SCHWARTZENBERG, a citizen of the United States, residing at Chicago, in the county of Cook and State of Illinois, have invented a certain new and useful Improvement in Draft-Yokes for Railway-Car Draft-Rigging, of which the following is a full, clear, concise, and exact description, reference being had 10 to the accompanying drawings, forming a part of this specification.

My invention relates to improvements in draft yokes for railway car draft rigging.

The object of my invention is to provide 15 a draft yoke adapted to be readily detached from the draw-bar.

In the drawings forming a part of this specification, Figure 1 is a plan view of a draft yoke embodying my invention; Fig. 2 20 is a side elevation thereof; and Fig. 3 is a cross-section taken on line 3-3 of Fig. 2.

Referring to the drawings, the numeral 4 indicates a U-shaped draft yoke comprising upper and lower limbs 5 and 6, respectively, 25 and the preferably integral rear connecting member 7. In preferable construction, a filler block 8 is secured to the inner face of the member 7 by suitable means, preferably the rivet 9. The free end of each limb of 30 the yoke is provided with a transverse vertically arranged T head 10 forming outer shoulders 11-11 and inner shoulders 12-12. The draw-bar 13, the rear end of which is shown in Fig. 2 of the drawings, is of the 35 usual type having the oppositely arranged shoulders 14-14 adapted to engage against the shoulders 12-12 of the free ends of the yoke. The yoke is secured to the draw-bar by means of a pair of loops 15-15 and a 40 coupler key 16. The loops 15-15 are identical in construction, each having a trans- 45 verse portion 17 adapted to engage a limb of the yoke, the forward edge 18 of each being adapted to engage against a shoulder 11 upon the yoke, and each of said loops having side plates 19-19 adapted to straddle the draw-bar. In assembled position, 50 one of said loops engages the upper limb 5 of the yoke, and another loop engages the lower limb 6 of the yoke. When so en-

gaged, the lateral perforations 20-20 in either plate 19 register with the perforation 21 in the draw-bar and receive the coupler key 16. One of the plates 19 of each loop has an outward bend 22 therein to permit 55 the passage of said plate along the outer face of the straight plate of the opposed loop, thus forming a substantially rectangular opening 23 within the loops when in assembled position in which the draw-bar is 60 received. In engaging the draw-bar to the yoke, the draw-bar is placed in position therein its shoulders engaging against the inner shoulders formed by the T-heads at the free ends of the yoke, one of the loops 65 placed in position in engagement with one limb of the yoke, and another loop placed in position in engagement with the other limb of the yoke, and the coupler key passed through the perforations in the loops and 70 through the draw-bar. To disengage the draw-bar from the yoke, the operation is reversed.

I claim:—

1. In a draft rigging for railway cars, in 75 combination, a draw-bar, a U-shaped yoke strap engaging the draw-bar at its free ends, a pair of independent counterpart loops passing around the yoke strap, and means to secure said loops to the draw-bar, each of 80 said loops having a straight wing and an out-turned wing, the out-turned wing of one loop being disposed adjacent the straight wing of the other loop.

2. In a draft rigging for railway cars, the 85 combination with a draw bar having shoulders on top and bottom thereof, of a yoke having shouldered enlargements at the ends of the arms thereof adapted to engage the draw bar shoulders, a pair of counterpart 90 loops having over-lapped sides and passing around the yoke and draw-bar butt, said loops also engaging said enlargements on the ends of the yoke strap, and means to secure said loops to the draw bar, said enlargements on the ends of the yoke arms being engaged by the draw bar shoulders and the loops upon forward movement of the draw bar to thereby cause the yoke to move 95 with the draw bar.

3. A device of the character described comprising a U shaped yoke having the ends of the arms thereof provided with T shaped heads, of a pair of substantially U shaped loops arranged to have their sides overlapped, said loops having shoulders arranged to engage the outer portions of said

T shaped heads, the overlapped sides of said loops being provided with aligned slots adapted to receive a coupler key.
